E. CARETTA

LIFTING JACK

Original Filed June 6, 1922

Fig. 1

Attys.

UNITED STATES PATENT OFFICE.

ETTORE CARETTA, OF TURIN, ITALY.

LIFTING JACK.

Original application filed June 6, 1922, Serial No. 566,276. Divided and this application filed August 6, 1923. Serial No. 656,086.

To all whom it may concern:

Be it known that I, ETTORE CARETTA, subject of the King of Italy, residing at Turin, Italy, have invented certain new and useful Improvements in Lifting Jacks, of which the following is a specification.

This invention relates to lifting jacks and more particularly to jacks for lifting vehicles, comprising a stationary base, a lifting member movable in said base and a collapsible chamber arranged between said base and member, this chamber being adapted to receive a fluid under pressure for the purpose of lifting said member and its load.

According to the present invention a jack of the kind above referred to is provided with means for admitting in said collapsible chamber a gas charge from a receptacle or cartridge in which said gas is stored in liquid state (known as "sparklets") this gas being permitted to expand in said chamber and producing therein the lifting pressure.

A constructional form of an improved jack according to the present invention is illustrated by way of example on the annexed drawing in which:—

Figure 1 is an axial section of the improved jack in its normal position before lifting;

Figure 2 is a similar section showing the lifting member in a raised position.

In the illustrated example the improved jack comprises a hollow stationary base 1 open at the top, and in the mouth 2 of which there is mounted so as to be capable of vertical motion a tubular lifting member 3.

This lifting member carries an adjustable head 4, preferably by means of a screw-threaded spindle 5 screwing in a screw-threaded hole in the top 6 of the lifting member 3.

Said member 3 is provided with an abutment 3' for stopping it when it has reached its uppermost position.

Between the inside wall of the base 1 and the outside wall of the member 3 there is a space in which is located a flexible chamber 7 having preferably the shape shown on the drawing, which is such that its upper half is readily capable of collapsing into its lower half as shown in Figure 1.

Said chamber 7 is made of suitable material, for instance rubber, so as to be ca-

pable of being inflated and expanding under internal pressure from the shape shown in Figure 1 to that shown in Figure 2. In the case of rubber, the wall of the air chamber 7 is preferably reinforced by a network 60 7' of suitable material incorporated in the rubber for the purpose of giving it the strength necessary for withstanding high internal pressures while avoiding the necessity of enclosing said chamber in an outer 65 cover.

In order to effect the inflation of the chamber 7 by using cartridge or receptacles filled with a compressed gas in liquid state (such as liquid carbonic acid) the collapsible chamber 7 is provided with a union 8 comprising a socket 9 forming a mouth. A perforated needle 10 is arranged centrally in the mouth of said socket and has its perforation opening in the passage of the 75 union 8. Said socket mouth is provided with a packing washer 19 and has an outer screw-thread on which is threaded a sleeve 20 of a support 11 intended to receive a cartridge 12 and having an abutment 21 for 80 the cartridge end as well as a rib 17 for grasping and manipulating it.

Said cartridge 12 contains a gas in liquid state, as carbonic acid, and its mouth is closed by means of a metal plug (not 85 shown) adapted to be perforated by the needle 10.

For the operation, the jack is located under the load and its lifting head 4 is carried in contact with the said load by manipulating the screw 5; then a cartridge 12 is located in the support 11 and its mouth is inserted into the packing 19 and finally the support 11 is rotated by its rib 17 to force the cartridge 12 against the perforating pin 95 10. The cartridge plug is thus perforated and the cartridge space is put in communication with the chamber 7 through the perforation of the pin 10 and the passage of the union 8; owing to the increase in volume 100 free for the cartridge content, the gas enclosed in it in liquid state is permitted to expand and to enter in gaseous state the chamber 7 to inflate it and to raise the lifting member 3 supported thereby and the 105 load. The parts are thus carried in the position shown by Figure 2 in which the chamber 7 is shown in its expanded shape.

The improved jack is very light because 110 all gearing is done away with; it can be

2
operated in a very simple manner by the use of small bottles or sparklets of liquid carbonic acid for the purpose of generating the requisite pressure in the air chamber 5 enclosed between the stationary base 1 and the lifting body 3. This lifting body or member 3 is preferably hollow and closed at the top by means of a plug or cover 6 so that it can be utilized as a container for 10 storing a suitable number of sparklets 12 to be employed for operating the jack.

The space left free intermediate the base wall and the wall of the lifting member 3 is preferably small; as shown, for the purpose of reducing to a minimum the portion 15 22 of the chamber 7 subjected to pressure and not supported by rigid parts, and therefore the tensile stress acting on said chamber.

Attention is called to my copending application No. 566,276, filed June 6, 1922, in respect of features not claimed per se in this application, but described or illustrated.

What I claim as my invention and desire to secure by United States Letters Patent 25 is:—

1. A fluid operated lifting jack comprising a hollow base, a member movable in said base, an inflatable collapsible chamber between said base and member, a receptacle 30 containing a gas charge in liquid state, and means for putting said receptacle in communication with said chamber to produce a lifting pressure therein.

2. A fluid operated lifting jack comprising a hollow base, a lifting member movable in said base, an inflatable collapsible chamber between said base and member, a receptacle containing a gas charge in liquid condition, means for connecting said receptacle 35 with said chamber and means for opening said receptacle to introduce said gas in said chamber and produce a lifting pressure therein.

3. A fluid operated lifting jack comprising a hollow base, a lifting member movable in said base, an inflatable collapsible chamber between said base and member, a union connected with said chamber, a support on 45 said union, a receptacle containing a gas charge in liquid condition adapted to be arranged in said support, cooperating means 50 on said union and support for putting said

receptacle in communication with said chamber to introduce said gas in said chamber and to produce a lifting pressure therein. 55

4. A fluid operated lifting jack comprising a hollow base, a lifting member movable in said base, an inflatable collapsible chamber between said base and member, a union 60 connected with said chamber, a support on said union, a receptacle containing a gas charge in liquid condition adapted to be arranged in said support with its mouth in register with said union, means in said union 65 for perforating the mouth of said receptacle, cooperating means on said support and union for forcing said receptacle with its mouth against said perforating means for the purpose of introducing said gas in said 70 chamber and producing a lifting pressure therein.

5. A fluid operated lifting jack comprising a hollow base, a lifting member movable in said base, an inflatable collapsible chamber between said base and member, a union 75 connected with said chamber, a support on said union, a receptacle containing a gas charge in liquid condition adapted to be arranged in said support with its mouth in 80 register with said union, means in said union for perforating the mouth of said receptacle, a screw-threaded portion on said union and a screw threaded collar on said support engaging said screw threaded portion of said union for forcing said receptacle with its mouth against said perforating means, for the purpose of introducing said 85 gas in said chamber and producing a lifting pressure therein. 90

6. A fluid operated lifting jack comprising a hollow base, a lifting member movable in said base, an inflatable collapsible chamber between said base and member, a receptacle containing a gas charge in liquid condition, means for putting said receptacle in communication with said chamber to produce a lifting pressure therein and an adjustable load supporting head on said lifting member, this lifting member being hollow for storing therein said receptacles to be used in connection with the jack. 95

In testimony whereof I have signed my name to this specification.

ETTORE CARETTA.
